UNITED STATES PATENT OFFICE.

FRANK HUMPHRIS, OF PARKSTONE, DORSET, ENGLAND.

PERFORATED OR EXPANDED SHEET METAL.

Application filed May 12, 1927, Serial No. 190,939, and in Great Britain April 27, 1927.

This invention relates to improved perforated or expanded sheet metal which is made from sheet metal perforated and bent, or slit and so expanded and bent that all 5 the so-called connective bars or strands, which constitute the mesh-work thereof or result during its manufacture, are curved or bent in such a manner that they project in the form of arcuated mesh-work having rows 10 of arcuated connective bars or strands located on one side and rows of arcuated connective bars or strands located on the other side of any resulting piece or sheet of such perforated or expanded sheet metal.

15 When giving form to the said arcuated connective bars or strands on a piece or sheet of metal an equal or approximately equal number of such arcuated connective bars or strands are arranged to project, each 20 in an arch-wise manner from each face of such piece or sheet of perforated or expanded metal and thus form edgewise apertures or openings in or through which either plain or screw threaded bars, rods, tubes or strips 25 of metal or the like may be placed to serve as additional reinforcing mediums where increased strength or rigidity is required.

Where sheet metal is specially perforated or where blanks have been cut from a piece 30 or sheet of sheet metal leaving as a residue perforated metal having connective bars or strands, such connective bars or strands are curved or bent into arcuate form and a convenient way of carrying this into effect is 35 to firstly arch, curve or bend one connective bar or strand in one direction, and to arch, curve or bend the immediately adjacent connective bar or strand in an opposite direction, and the next one back again in an 40 opposite direction, and so on, in such a manner as to form two groups of arcuated connective bars or strands in which the crowns of one group extend in one direction from one side of the general plane of such piece 45 or sheet of metal and the crowns of the other group extend in the opposite direction from the other side of said plane. Alternatively instead of bending one connective bar or strand in one direction and the next 50 one to it in an opposite direction, two or more adjacent connective bars or strands may be bent in one direction and the next two or more in an opposite direction and so on, such arch-wise bending forming the hereinbefore 55 referred to edgewise apertures or openings.

The arcuated connective bars or strands of perforated metal or perforated metal residue or expanded metal are connected together at junctions of flat or V-like form in cross-section which, when increased rigidity is required, are creased, ridged or grooved longitudinally or transversely or in both directions; and the said arcuated connective bars or strands may also be given a channelled or sinuous form in cross-section for 60 a like purpose.

The arcuated connective bars or strands of the mesh-work of the expanded metal in addition to being curved or bent into an arcuate form, are also so shaped that meshes 70 having a cupped, concave-wise, countersink-like or bell-mouthed form result; and meshes so shaped are hereinafter referred to collectively as principle rows of meshes or mesh-work, or individually as a principal 75 mesh so as to distinguish them from other rows of meshes hereinafter referred to as intermediate rows of meshes or mesh-work or from any individual intermediate mesh. Each mesh in each principal row of mesh-work has integral junction at the widest part 80 of the so-called short way of its mesh with another principal mesh in the next principal row of mesh-work thereto. Each principal row of mesh-work has its meshes inverted 85 in relation to the meshes of that principal row of mesh-work to or with which it is integrally connected, and between any two such principal rows of mesh-work there is located one row of the hereinbefore referred 90 to intermediate rows of mesh-work, and each intermediate mesh is formed by parts of the arcuated connective bars or strands of four integrally connected principal meshes of any two integrally connected principal 95 rows of mesh-work.

Sheet metal, slit, expanded and bent according to this invention with principal meshes of a cupped, concave-wise or countersink-like form and with each principal row 100 of mesh-work inverted in relation to the next principal row of mesh-work thereto, has greater rigidity than other known forms of perforated or expanded metal having connective bars and meshes of the same size formed 105 and of the same quality of material.

In expanded metal made according to this invention the junction where each connective bar or strand meets at the end of the long way of each principal mesh, is creased 110

or of V-like form in cross-section and is also optionally ridged or grooved; and the junction located at the widest part of the short way of each principal mesh, where it is integrally connected to another principal mesh in another principal row of mesh-work, is not of V-like form but is what may be described as approximately flat or of a sinuous form in cross-section and, to give it greater 10 rigidity, it may be grooved.

An object of this invention is to provide rigid sheets or pieces of perforated metal, perforated metal residue, and expanded metal having edge-wise apertures or openings through which there may be passed, or in which there are placed so as to remain therein, reinforcing bars or tubes or strips of metal or the like, in such a manner that such bars or the like are embraced by or lie between the arcuated connective bars or strands or so that the said reinforcing bars or the like are at right angles or thereabouts to the length-wise direction of the so-called long way of the meshes.

Another object of this invention is to provide expanded metal having principal meshes of cupped, concave-wise or countersink-like form with each principal mesh inverted in relation to the principal mesh next to it and with which it makes junction at the widest part of the so-called short way of the mesh, thereby forming intermediate rows of mesh-work, and edge-wise apertures or openings through which it is possible to pass reinforcing bars or the like equivalents.

The invention will now be described with reference to the accompanying drawings which are given merely by way of example, in which:

Figure 1 is a face view and edge view illustrating five separate pieces of part of a sheet of the perforated metal residue, the upper portion showing such residue before the connective bars or strands have been given arcuate form, the other four pieces showing examples after the connective bars or strands have been given arcuate form and also how reinforcing mediums such as rods or the like may be passed between the arcuated connective bars or strands and through the edge-wise apertures or openings which are clearly shown in the edge view of this figure.

Figure 2 is an edge view of a sheet of the perforated metal, to illustrate the edge-wise apertures or openings and how the connective bars or strands are curved or bent, some in one direction and some in a reverse direction relative to the general plane of such sheet of perforated metal.

Figure 3 is a plan view of a piece of a sheet of the expanded metal, showing the V-like and the so-called flat junctions of the principal rows of mesh-work and how each principal mesh in each principal row of

mesh-work is of a cupped, concave-wise or countersink-like form and is inverted in relation to each principal mesh in the next principal row of mesh-work thereto and also how reinforcing mediums are passed between 70 the arcuated connective bars or strands and through the edge-wise apertures or openings.

Figure 4 is an edge view of Figure 3 to illustrate more clearly how the arcuated connective bars or strands are curved or bent, 75 some in one and some in a reverse direction, thus forming the edge-wise apertures or openings in and through some of which reinforcing mediums are shown.

Figure 5 is a view, partly in section, on an enlarged scale, of a piece of the perforated metal residue to illustrate the ridging or grooving of the junctions and the arcuated connective bars or strands for the purpose of increasing their rigidity.

Figure 6 is an end view enlarged, partly in section, on the line A—B Figure 3 illustrating the flat junctions between principal rows of mesh-work which are inverted in relation one to another; this view also clearly 90 shows the V-like junctions. A reinforcing bar is shown passed through the edge-wise apertures or openings.

Figure 7 is a plan view of a piece of the expanded metal showing reinforcing rods 95 located between the V-like junctions of the arcuated connective bars or strands; this figure illustrates clearly the cupped, concave-wise, countersink-like or bell-mouthed form given to each principal mesh in each 100 principal row of mesh-work and how each principal row of mesh-work is inverted in relation to the next.

Figure 8 is a view to show how the flat junctions and the arcuated connective bars 105 or strands are optionally grooved or channelled to increase their rigidity.

Figure 9 is a view to show how the V-like junctions and the arcuated connective bars or strands are optionally grooved or channelled to increase their rigidity.

Figure 10 is an end view of Figure 7.

Like letters of reference refer to like parts throughout the drawings.

Convenient methods of carrying this invention into effect are clearly illustrated and by referring to Figure 1 of the drawings the upper portion of this figure illustrating a piece of part of a sheet of perforated metal, before any of its connective 120 bars or strands have been given arcuate form, the piece below it having arcuated connective bars or strands *a* alternately so bent or formed as to be curved in opposite directions, thus forming edge-wise apertures or 125 openings *b* clearly seen in Fig. 2, and it is through these apertures or openings *b* that the bars or the like *c* as shown are optionally placed; the piece midway of Figure 1 shows another form of placement for the arcuated 130

- connective bars or strands *a*; the piece immediately below the piece just referred to illustrates how two adjacent arcuated connective bars or strands *a* project in one direction and the next two arcuated connective-bars or strands *a* project in a reverse direction; the piece at the bottom of Figure 1 illustrates how three adjacent arcuated connective bars or strands *a* project in one direction and the next three arcuated connective bars or strands *a* project in a reverse direction. The edge-view of each of the four lower pieces illustrated in Figure 1 shows the edge-wise apertures or openings *b* which result, with bars or the like *c* therethrough, but it is to be understood that any number of adjacent connective bars or strands may be curved in any one and in any reverse direction.
- 20 The use of bars, rods or the like *c* as shown in each of the edge-wise apertures or openings *b* in Figure 1 is optional and occasional as metal having connective bars or strands *a* arcuated according to this invention is extremely rigid.

Figure 2 of the drawings is an edge view of a piece of my improved perforated metal with arcuated connective bars or strands *a*, illustrated partly in section, its junctions *d* being creased or grooved at *d*¹ to increase their rigidity. The edge-wise apertures or openings *b* in this view are shown without rods, bars or the like *c* therethrough.

The plan views of the pieces of sheets of my improved expanded metal shown in Figures 3 and 7 illustrate how the arcuated connective bars or strands *a* project, some in one direction and some in a reverse direction. These views also illustrate how each principal mesh *f* in each principal row of mesh-work F—F is inverted in relation to each principal mesh *g* in each or the next principal row of mesh-work G—G and how each principal mesh *f* is integrally connected to a principal mesh *g* by a so-called flat junction *d* in such a manner that there are between each two integrally connected rows of mesh-work F—F and G—G, intermediate rows of mesh-work H—H consisting of meshes *h* which are the result of the method of expanding my improved expanded metal and due to the form of placement of the V-like junctions *e* and the junctions *d* on the principal meshes *f* and *g*. The cupped, concave-wise, countersink-like or bell-mouthing form of each principal mesh *g* in each principal row of mesh-work G—G is clearly illustrated in Figures 3 and 7 wherein, in which rods, bars or the like *c* are shown in position between some of the arcuated connective bars *a* and through some of the edge-wise apertures or openings *b*.

Each edge-wise aperture or opening *b* is formed as the result of giving arcuate form 65 to the connective bars or strands *a*, as is

clearly shown in Figure 4, which is an edge view of Figure 3, and in both of these figures bars, rods or the like *c* are shown extending through some of the edge-wise apertures or openings *b* in some of the positions they would occupy, if or when employed.

The junctions *d* and the arcuated connective bars or strands *a* of my improved perforated metal are optionally channelled or grooved and a convenient method of carrying this into effect is illustrated in Figure 5.

When rods, bars or the like *c* are used and passed through the edge-wise apertures or openings *b* of a piece or sheet of my improved expanded metal, the V-like junctions *e* are so located that they are contiguous to the said bars, rods or the like *c*, this can be clearly seen in Figures 6 and 10 of the drawings.

Both the V-like junctions *e* and the flat-junctions *d* of my improved expanded metal are optionally creased, ridged or grooved at *d*¹ when it is desired to make them more rigid, as are also the arcuated connective bars or strands *a* and convenient methods of carrying this into effect are shown in Figures 8 and 9 of the drawings.

I claim:

1. Sheet metal perforated to form a mesh-work having the junctions of the meshes lying in one plane, and the connective bars forming the strands of the mesh bent alternately outward from the opposite sides of said plane to form edge-wise apertures.

2. Sheet metal perforated to form a mesh-work comprising contiguous principal rows of meshes connected at junctions to form intermediate rows of meshes, the strands forming each mesh of the principal rows being arcuate and curved in opposite directions to one another to form edge-wise apertures, the junctions of the meshes lying in a median plane between the envelope planes of the strands of opposite curvature.

3. Sheet metal perforated to form a mesh-work comprising arcuate strands forming principal rows of meshes, the junctions of the meshes lying in a median plane, the strands of any one row lying on one side of a median plane of the sheet and the strands of adjacent rows lying on the opposite side of the said plane.

4. Sheet metal perforated to form a mesh-work having arcuate unstretched connective bars forming the strands of the mesh respectively bent outwardly in opposite directions from a median plane.

5. Sheet metal perforated to form a mesh-work comprising arcuate strands forming principal rows of meshes with the points of junction in the same row situated in the same plane, the points of junction in adjacent rows being in different planes and the points of junction of each principal row with the adjacent principal rows being sit-

uated in one plane lying between the said different planes.

6. Sheet metal perforated to form a mesh-work having the material at the points of junction of grooved cross section, the junctions of the meshes in each row being in a median plane and the junctions of the meshes of one row with adjacent rows being

respectively on opposite sides of the said median plane.

7. Sheet metal perforated to form a mesh-work having the connective bars forming the strands of the meshes bent to form edge-wise apertures and rods inserted through the said edge-wise apertures.

FRANK HUMPHRIS.
